By Clarence A. D. Price
Attorney

UNITED STATES PATENT OFFICE.

MICKEY FRANZ, OF PUEBLO, COLORADO.

WINDOW-SHADE-ROLLER BRACKET AND ACTUATING DEVICE.

Application filed June 2, 1925. Serial No. 34,401.

The present invention relates to a device for use in connection with shade rollers and the like, in order that they may be supported on the window frame, or like support, and in order that they may be easily operated without the necessity of handling the curtain.

Another important object of the invention is to provide a device of this nature which may be used in place of the ordinary spring roller.

Another important object of the invention is to provide a device of this nature having a brake mechanism associated therewith for engagement with the shade roller to prevent accidental rotation thereof.

A still further very important object of the invention is to provide a device of this nature which is exceedingly simple in its construction, strong, durable, one which is efficient and reliable in its use, inexpensive to manufacture, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:—

Figure 1 is a fragmentary elevation of a window frame showing my improved device associated therewith as in actual use.

Figure 2 is a vertical detail section taken substantially on the line 2—2 of Figure 1 looking to the left.

Figure 3 is a detail perspective view of one of the brackets, and

Figure 4 is a detail perspective view of one of the brake jaws.

Referring to the drawing in detail it will be seen that A designates a window frame or the like with which is adapted to be associated the shade B and the roller C. This roller C may be of the conventional spring type, or of any other suitable formation. The parts thus far described are all of conventional, or any well known or desirable construction and do not form a part of my invention, but are illustrated merely to bring out more clearly the utility and novelty of my improved device.

Referring particularly to my improve-

ment it will be seen that the letter D indicates generally one of the brackets which includes a body plate 5, and a rectangularly disposed flange 6 at one end. The flange 6 is provided with apertures 7 in order that suitable fastening elements such as screws 60 may be inserted therethrough for securing the bracket onto the window frame A. On the upper and lower edges of the flange 6 there are provided a pair of curved loops 8. On the lower edge of the body 5, a pair of 65 curved loops 9 are formed which are in horizontal spaced relation. A tongue 10 is cut from the body 5 vertically starting from the upper edge thereof and is bent outwardly, and then under over upon itself, as 70 may be seen particularly in Figure 1.

The brake mechanism includes a pair of jaws, each of which is indicated generally by the letter E, and includes an intermediate arcuate shaped portion 12 terminating in straight ends 13 and 14, the former of which is provided with an aperture 15, and the latter with a T-head 16. The T-heads 16 are engaged in the loops 8 at the top and bottom edges of the flange 6, and a bolt 17 80 passes through the apertures 15 and has a nut 18 on its upper end, a spring 19 is coiled about the bolt 17 between the lower end 13 of the lower jaw E, and the head 20 of the bolt, and tends to hold the jaws in frictional 85 engagement with the roller C, which has its pintle 21 in the slot 22 left by the tongue 10, and rests on the horizontal upper portion of said tongue as clearly illustrated in Figure 1. A band 23 of annular construction is disposed about the roller C being fixed thereto in any suitable manner and is provided with a plurality of spaced cross ribs forming teeth so that a chain 24 may be trained there-over. This chain is extended through the 90 guide loops 9. It will therefore be seen that upon pulling the chain 24, the roller C may be rotated, and that the brake mechanism including the jaws E will hold the roller in any desired position to which it 100 may have been rotated by actuation of the chain 24. It will thus be seen that I have provided a device which not only efficiently supports the shade roller, but allows the same to be easily rotated to put the shade at a desired position, and furthermore the brake maintains the roller in a position to hold the shade at a desired height as to the window.

It is apparent that the device is capable of use without any kind of a roller, and is not necessarily confined to a shade roller.

The present embodiment of the invention 5 has been disclosed merely by way of example, and attains all the features of advantage enumerated as desirable in the statement of the invention and the above description. It will be apparent that numerous 10 changes in the details of construction, and in the combination and arrangement of parts may be resorted to without departing from the spirit or scope of the invention as hereinafter claimed or sacrificing any of its ad- 15 vantages.

Having thus described the invention, what I claim as new and desire to secure by Letters Patent is:—

A bracket for a shade roller; wherein the

shade roller is provided with a sprocket hav- 20 ing a chain trained thereover and has asso- ciated therewith, a pair of spring pressed 25 brake members; comprising a plate in which an end of the roller is adapted to be jour- naled, a pair of spaced guide loops formed 30 integrally with the lower edge of the plate, said loops adapted to receive runs of the chain, a flange formed integrally with one side edge of the plate and extending rectan- gularly therefrom, two pairs of loops formed 35 on the flange, one on the upper edge thereof and one on the lower edge thereof, the loops of each pair being spaced from each other and aligned for receiving pivots of the brake members.

In testimony whereof I affix my signature.

MICKEY FRANZ.
